LOOM TRANSFER REVOKING
MECHANISM

Richard G. Turner, Worcester, Mass., assignor to
Crompton & Knowles Loom Works, Worcester,
Mass., a corporation of Massachusetts

Application May 23, 1936, Serial No. 81,442

10 Claims. (Cl. 139—231)

This invention relates to improvements in means for preventing the completion of a transfer upon the occurrence of weft breakage and it is the general object of the invention to prevent 5 a bobbin in transfer position from falling on to the lay should the loom be stopped by a center filling stop motion.

In weft replenishing looms the bobbin next to be inserted into the exhausted shuttle lies under 10 a transfer arm which usually is depressed by a connection with the lay as the latter advances. With fine filling it is customary to use a center stop motion which stops the loom before the lay strikes the fell of the cloth. Since transfer is 15 dependent upon lay motion and is completed when the lay is in its foremost position, a stoppage of the loom by the center stop motion will cause an incomplete transfer, leaving the reserve bobbin on the shuttle or some part of the lay to 20 cause damage. It is an important object of my present invention to provide a connection between the filling stop motion and the weft replenishing mechanism effective to prevent any motion of a transerrer arm which would move 25 the reserve bobbin out of the magazine.

In order to insure prompt stopping of the loom when the center stop motion is used there is generally provided a brake controlled by a handle which is moved to stopping position by the center stop motion. This handle is conveniently 30 near the weft replenishing mechanism and it is a further object of my invention to establish a connection between the brake handle and the transfer latch on the transerrer arm operative 35 to move the latch out of engaging position with respect to the lay when the brake handle moves to stopping position.

In multicolor weft replenishing looms as customarily built in this country the magazine is 40 provided with a vertically controlled slide for each stack of reserve bobbins and the magazine is reset with the vertical slide down at the completion of the transfer operation, thereby rendering the magazine incapable of repeating a transfer from a single indication of a weft detector. It is another object of my present invention to 45 employ the center stop motion not only for stopping the loom with the lay in a relatively rearward position and revoke transfer, but also to reset the magazine so that there will be no danger of a second transfer unless called for by a second indication of the weft detector. Under these circumstances the magazine is reset without requiring the lay to come to its foremost posi-

tion as is customary in the ordinary weft replenishing loom of the multicolor type.

By the use of my invention it will be understood that the center stop motion can stop the loom on a pick indicated for transfer with the 5 lay in a relatively rearward position without likelihood of a reserve bobbin being discharged from the magazine, thereby avoiding any damage which would otherwise occur should the bobbin be advanced toward the lay by an incomplete 10 transferring operation.

With these and other objects in view which will appear as the description proceeds, my invention resides in the combination and arrangement of parts hereinafter described and set forth. 15

In the accompanying drawings wherein a convenient embodiment of my invention is set forth,

Fig. 1 is an end elevation of a portion of a loom having my invention applied thereto,

Fig. 2 is a detailed rear elevation looking in the 20 direction of arrow 2, Fig. 1,

Fig. 3 is a transverse section through a portion of the loom showing the lay advancing and with the center stop motion in normal position,

Fig. 4 is similar to a portion of Fig. 3 but showing the center stop motion operative to apply the brake of the loom,

Fig. 5 is an end view on an enlarged scale in the direction of arrow 5, Fig. 1, and

Fig. 6 is a diagrammatic view showing the relation between the lay carried bunter and dagger and the parts they operate.

Referring to the drawings, the loom frame 10 has mounted for rotation therein a shipper shaft 11 on which is pivoted a brake handle 12. The 35 latter has a depending finger 13 carrying a pin 14 received by slot 15 in a rocking lever 16 pivoted at 17. The lower end of lever 16 is connected to a link 18 attached to a brake operating bar 19 extending rearwardly or to the right as viewed in 40 Fig. 1 to have connection with the brake motion not shown of the loom. When the parts are in the running full line position shown in Fig. 1 bar 19 is elevated, but when handle 12 moves to the rear stopping dotted position shown in Fig. 1 45 the pin 14 moves out of a notch 20 at the upper end of slot 15 and the lever 16 rocks in a left hand direction with a corresponding down motion of the bar 19 to brake the loom.

A sleeve 25 surrounds the shipper shaft 11 and 50 has the brake handle secured thereto. The latter carries a lug 27 positioned for engagement with a knock-off set screw 28 carried by and adjustable with respect to a shipper handle 26 secured to the shipper shaft. A locking pin 29 on 55

the shipper handle rests in a notch 30 in a shipper lever 31 when the loom is running, the lever 31 when in the running left hand position shown in Fig. 1 drawing rods 32 and 33 forwardly to clutch the loom for driving. When the shipper handle moves to the dotted stopping position shown in Fig. 1 the lever 31 is free to move to the right from the position shown in Fig. 1, thereby unclutching the loom in the usual manner. It is not deemed necessary to show either the shipping or braking mechanism and it is considered sufficient to state that when the brake handle moves to the dotted line position of Fig. 1 the brake will be immediately applied and will be set tight enough to bring the loom to rest while the lay is moving forwardly and before it reaches front center position.

The magazine M supported by the loom frame is of the customary multicolor type and includes reserve bobbin guideways 35 and bobbin supports 36 and 37 which may be located respectively in front of and behind a bobbin B held on them in transfer position. A transfer arm 38 pivoted as at 39 carries a latch holder 40 to which is adjustably secured a latch 41 to engage a bunter 42 on the lay L. The shuttle S travels along the lay toward the magazine end of the loom when it is to be replenished by the bobbin B.

Referring to Fig. 5, the magazine has vertical slides 43 which extend downwardly to release mechanism for the stored bobbins not shown, and each slide has pivoted to the upper end thereof a dog 34 which is normally in the down, closed full line position. A shelf 44 is secured to a shaft 45 and is normally in the raised dotted line position of Fig. 5 when the loom is not set for transfer. When indication of weft exhaustion is given the slide 43 corresponding to the indicating shuttle is raised to the dotted line position of Fig. 5 in the usual manner by mechanism not shown and the dog is then free to move over a portion of the shelf 44, as indicated in dotted lines. At a later time the elevated slide 43 will be depressed, thereby lowering the shelf 44 to the full line position of Fig. 5. The shaft 45 is journaled in the magazine frame and has secured thereto an arm 46 carrying a block 47 which slides in a slot 48 located in the left arm 49 of a yielding lock lever 50 movable about a fixed axis 51. A stop screw 52 on arm 49 is positioned for engagement with a portion 53 of the magazine. The right arm 54 of the lever 50 is connected to a depending rod 55 which passes under the normally down latch 41.

When the shelf 44 moves down lever 50 is rocked in a left hand direction to elevate rod 55 and move the latch 41 from the dotted to the full line position shown in Fig. 1. In this position the latch is located for engagement with and in the path of a lay bunter 42 as the latter advances to effect downward motion of the transfer arm and cause transfer of the reserve bobbin B into the shuttle S in known manner.

When the lay reaches front position and the transfer is completed the magazine will be reset, the means for accomplishing this result being shown herein as a cam face 57 extending downwardly and rearwardly on the under side of the latch 41, forward motion of the latch under influence of the lay causing downward motion of the rod 55 to rock the yielding lock shown in Fig. 70 5 back to normal position. A fixed guide 58 prevents forward motion of rod 55, assisting cam 57 to lower said rod. It is customary to employ additional means for resetting the magazine but the cam on the under side of the transfer latch 75 is considered sufficient for present purposes to

set forth means whereby downward motion of rod 55 induced by the advancing latch will act to reset the magazine. The magazine set forth herein may be of the usual construction such as shown, for instance, in prior patent to Ryon No. 1,030,748.

When the finer grades of yarn are woven it is customary to employ a center stop motion located on the lay between the selvages of the fabric being woven. Such a stop motion detects every 10 pick of weft and operates sufficiently early to stop the loom before the reed can strike the fell of the cloth. I have shown a conventional center stop motion in Figs. 3 and 4, wherein it will be seen that the lay carries a bracket 60 through which extends a small shaft 61 carrying a drum 62 and the tines 63 of the filling fork fall into a well 64 when weft is absent. A link 65 is pivoted to the drum and is connected to a lever 66 acted upon by a rod 67 extending upwardly from a point behind the axis of the lay. In this way the dagger 68 carried by lever 66 is permitted to move upwardly in known manner if the tines 63 fall into the well 64 because of weft absence. If, on the other hand, weft is present in the shed, the 25 tines are supported and relative upward movement of the dagger with respect to the lay is arrested.

The breast beam 69 carries a bracket 70 having a shaft 71 provided with a lug 72 having a notch 73 to receive the dagger 68. A knock-off arm 74 is secured to the shaft 71 and engages a second arm 75 secured to the sleeve 25. A dagger shield 76 swings around the shaft 71 and has an upwardly extending resetting finger 77 positioned for engagement with a part 78 of the lay. 35 A lug 79 moving with the shield is located for engagement with the light spring lock 80 secured to arm 75.

Under normal weaving conditions when weft is present the lay will move toward and from the breast beam 69 but the dagger 68 will be in relatively low position because of the fact that the weft in the shed supports the tines 63. When weft is absent, however, the dagger will rise to the dotted line position shown in Fig. 3 to enter notch 73, after which continued forward motion 45 of the lay will rock elements 72 and 74 in a counter clockwise direction as viewed in Fig. 3 to cause downward motion of the knock-off arm 75. This effects rocking of the sleeve 25, and the brake handle previously described as secured to 50 this sleeve will also rock, moving from the full to the dotted line position shown in Fig. 1 to apply the brake to the loom not shown.

If the magazine has previously been set for a transfer and has released a bobbin from one or another of the compartments 35 to be held by the supports 36 and 37, as shown in Fig. 1, on a pick of the loom when the filling stop motion rocks the brake handle to stopping position, the lay will come to rest a short distance behind the fell of the cloth. If under these conditions latch 41 should remain in its elevated full line position of Fig. 1 the transfer arm 38 would have a partial downward motion the effect of which would be to move the reserve bobbin B to a position below that suggested in Fig. 1, but not low enough to complete transfer into the shuttle S. The released bobbin would therefore be likely to break some part of the mechanism, and the present invention relates to means for preventing this improper release or incomplete transfer of the reserve bobbin.

In carrying my invention into effect I provide the brake handle with the rearwardly extending 75

finger 90 and pivot thereto the lower end of a link 91 which extends upwardly through a fixed guide 92 and is bent over latch 41, as at 94. When the brake handle is moved to the running left hand position shown in Fig. 1 the finger 90 is raised and the bent end 94 is therefore in its highest position where it cannot interfere with upward motion of the latch 41. Should the center stop motion act to stop the loom as already described 5 the brake handle will be rocked to the stopped dotted line position of Fig. 1 to cause depression of the finger 90 and link 91 to the dotted line position of that figure. Since the upper hooked end 94 engages the top of latch 41 in its descent, 10 said latch will be moved down to the dotted line position shown in Fig. 1 a short interval of time before the bunter 42 advances far enough to engage the latch. In this way operation of the center stop motion is caused to revoke the transfer, 15 thereby permitting the bobbin B to remain on the supports 36 and 37 without being subjected in any way to a transfer motion. At some later time this bobbin can be released by well-known mechanism not shown herein.

20 The relation of the lay-carried bunter and dagger, together with the transfer latch 41 and notched arm 72, is shown in Fig. 6. For convenience the notches 73 and 96 of latch 41 and arm 72, respectively, are indicated in vertical 25 alignment, lying along line *d*, while vertical line *e* for the front of dagger 68 is in front of line *f* corresponding to the front end of bunter 42. As the lay advances on a beat when stopping by the weft fork and a transfer are both called, 30 dagger 68 enters notch 73 first, and later, after an interval corresponding to distance *a*—*b* which is long enough to permit lowering of the latch 41 before the bunter can reach it the bunter passes over the latch without engaging it, there- 35 40 by avoiding transfer.

When the link 91 moves downwardly to depress the latch 41 the latter will act to lower the rod 55 resulting, as previously described, in a resetting of the magazine, particularly the parts 45 shown in Fig. 5. After the weaver has repaired the broken filling the brake handle will be moved back to its forward full line position of Fig. 1, thereby raising the link 91 and the loom will be ready for the initiation of another weft replenishing operation without further attention on the 50 part of the weaver.

From the foregoing it will be seen that I have provided a simple means whereby a previously indicated transferring operation of the magazine 55 can be revoked should the center stop motion act to stop the loom on the beat thereof intended for transfer. In this way the reserve bobbin resting on the supports 36 and 37 remains in the magazine without being ejected by an incomplete 60 operation of the transfer arm toward the lay. It will also be seen that the center stop motion acts to reset the magazine so that should the weaver, when repairing the broken filling in the shed, also effect replenishment by hand, there will 65 not be an unnecessary operation of the magazine. It is to be understood that the parts will be set in such a relation that the center stop motion will act to initiate loom stoppage by rocking of the sleeve 25 when the lay is a slight distance behind 70 the point at which the bunter 42 would ordinarily engage the latch 41. This setting of the parts permits sufficient time for the latch to move down out of the path of the bunter and thereby prevent any movement of the transfer arm.

75 Having thus described my invention it will be

seen that changes and modifications may be made therein by those skilled in the art without departing from the spirit and scope of the invention and I do not wish to be limited to the details herein disclosed, but what I claim is:

1. In a weft replenishing loom, a lay, a center filling stop motion effective to bring the loom to rest before the lay reaches its foremost position, means to hold a reserve bobbin in transfer position, transfer mechanism effective to complete a 10 transferring movement of the reserve bobbin when the lay reaches forward position, and means operated by the center stop motion when acting to stop the loom to prevent the transfer mechanism from engaging the reserve bobbin. 15

2. In a weft replenishing loom, a lay, a center filling stop motion on the lay effective to stop the loom with the lay in a relatively rear position, means to hold a reserve bobbin in transfer position, transfer mechanism to give the reserve bobbin a complete movement by a force derived from the lay when the latter is in its foremost position, and means controlled by the center stop motion and connected to the transfer mechanism to prevent operation of the latter when the center 20 25 stop motion stops the loom.

3. In a weft replenishing loom, a lay, a center stop motion on the lay effective to cause loom stoppage with the lay in a relatively rear position, means to hold a reserve bobbin in transfer 30 position, transfer mechanism dependent for its complete operation upon engagement and complete forward motion of the lay, and means controlled by the center stop motion and connected to the transfer mechanism to prevent operation 35 of the latter when the center stop motion stops the loom.

4. In a weft replenishing loom, a lay, a center stop motion on the lay effective to cause a loom to stop during the forward beat of the lay before 40 the latter reaches its foremost position, means to hold a reserve bobbin in transfer position, transfer mechanism for the reserve bobbin to be engaged by the lay as the latter moves forwardly and dependent upon complete forward motion of 45 the lay to effect transfer of the reserve bobbin, and means controlled by the center stop motion and connected to the transfer mechanism to prevent operation of the latter when said center stop motion causes the loom to stop. 50

5. In a weft replenishing loom, a lay, a center stop motion on the lay effective to initiate loom stoppage when the lay reaches a given point in the forward motion thereof and to cause loom stoppage before the lay reaches its foremost position, means to hold a reserve bobbin in transfer position, transfer mechanism for the reserve bobbin to be engaged by the lay at a point in front of the said point in the forward motion of the lay, and means controlled by the center stop motion and connected to the transfer mechanism 60 to prevent operation of the transfer mechanism. 55

6. In a weft replenishing loom, a lay, a center stop motion, a brake handle to control loom operation, means by which the center stop motion initiates movement of the brake handle toward stopping position when the lay is in a relatively rearward position, means to support a reserve 70 bobbin in transfer position, transfer mechanism for the bobbin dependent for operation thereof upon forward motion of the lay, and a connection between the brake handle and the transfer mechanism to prevent operation of the latter 75

when the center stop motion causes movement of the brake handle.

7. In a weft replenishing loom, a lay, a center stop motion on the lay to initiate loom stoppage during forward motion of the lay and effecting loom stoppage before the lay reaches forward position, a reserve bobbin magazine capable of being set to prevent a reserve bobbin for transfer of a transferring beat of the loom and reset to prevent a repeated transfer, transfer mechanism for the reserve bobbin, and means controlled by the center stop motion when acting to stop the loom to prevent operation of the transfer mechanism and reset the magazine.
8. In a weft replenishing loom, a lay, a center stop motion on the lay, a brake handle to be moved from running to loom braking position by the center stop motion when the lay is in a relatively rearward position, transfer means set to be operated by forward motion of the lay, and a connection between the brake handle and transfer means to move the latter out of the path of the lay when the center stop motion causes the brake handle to move to braking position.
9. In a weft replenishing loom, a lay, a center stop motion on the lay, a brake handle to be moved by the center stop motion from running to

loom braking position when the lay is in a relatively rearward position, weft replenishing mechanism including a latch, means to set the replenishing mechanism for transfer with the latch in the path of the lay, and a connection between the brake handle and latch operative when the center stop motion moves the brake handle to loom braking position to move the latch out of the path of the lay and reset the replenishing mechanism by a force transmitted through the latch. 5

10. In a weft replenishing loom, a lay, a center stop motion on the lay, a brake handle to be moved by the center stop motion from running to loom braking position when the lay is in a 15 relatively rearward position, weft replenishing mechanism including a latch, means to set the replenishing mechanism for transfer with the latch in the path of the lay, said latch when moved out of the path of the lay effective to reset 20 the replenishing mechanism, and a connection between the brake handle and latch to move the latter out of the path of the lay when the center stop motion moves the brake handle to stopping position to prevent transfer operation of the replenishing mechanism and also reset the latter. 25

RICHARD G. TURNER.
